UNITED STATES PATENT OFFICE.

PHINEAS C. HUDSON, OF MINNEAPOLIS, MINNESOTA, ASSIGNOR TO ARCHER TIRE & RUBBER COMPANY, OF MINNEAPOLIS, MINNESOTA, A CORPORATION.

DESIGN FOR A TIRE-CASING.

57,340.

Specification for Design.

Patented Mar. 15, 1921.

Application filed June 21, 1920. Serial No. 390,666. Term of patent 14 years.

To all whom it may concern:

Be it known that I, PHINEAS C. HUDSON, a citizen of the United States, and a resident of Minneapolis, county of Hennepin, State of Minnesota, have invented a new, original, and ornamental Design for a Tire-Casing, of which the following is a specification, reference being had to the accompanying drawing, forming part thereof.

Figure 1 is a plan view of a portion of a tire casing, showing my new design;

Fig. 2 is a section on the line 2—2 of Fig. 1.

I claim:

The ornamental design for a tire casing, as shown.

PHINEAS C. HUDSON.
